UNITED STATES PATENT OFFICE

JAMES P. SALMON, OF PHILADELPHIA, PENNSYLVANIA, ASSIGNOR OF PART INTEREST
TO JOHN W. FRANCE AND JOSEPH A. MISSAR, BOTH OF PHILADELPHIA, PENNSYLVANIA

SIGN

Application filed August 25, 1926. Serial No. 131,371.

My invention relates to new and useful improvements in a sign, and has for its primary object to construct a device of this character with three wings, each more than 5 ninety degrees from the other so that one or more of the surfaces will be visible from any point about the sign.

Another object of the invention is to construct a sign with three wings so as to 10 provide a plurality of display surfaces, one display surface on each side of each wing, so as to provide six such surfaces, or a surface between each pair of wings so as to provide three such surfaces, which latter 15 are preferably concave.

A still further object of the invention is to provide for illuminating all of the surfaces from a single source of light.

With these and other ends in view, this 20 invention consists in the details of construction and combination of elements herein-after set forth and then specifically designated by the claims.

In order that those skilled in the art to 25 which this invention appertains may understand how to make and use the same, I will describe its construction in detail, referring by numerals to the accompanying drawings forming a part of this application, in which:

Fig. 1, is a plan view of a sign constructed in accordance with my invention.

Fig. 2, is a front elevation thereof.

Fig. 3, is a plan view of a modified form of sign embodying the invention.

Fig. 4, is a front elevation of Fig. 3.

In carrying out my invention as embodied in Figs. 1 and 2, 5 represents a suitable base, from which projects a standard 6, and while for purposes of illustration I have 40 shown the base as a part of the standard, it is to be understood that this base may be a cement mass in a hole in the ground or the ground itself.

From the upper end of the standard project 45 three wings 7, 8 and 9, each radiating from the longitudinal or vertical center of the standard, and at more than ninety degrees apart, so as to provide surfaces 10 on each side of each wing, thereby giving six 50 surfaces, on which display information of

any character, such as traveling directions or advertisements is shown, and it is to be understood that each surface may be divided into sections for the display of different information, or the adjacent surfaces of two 55 adjacent wings may be used for the display of information on one subject.

For use at night, I provide a suitable arched supporting frame 11 to hold the lamp 12 above the meeting points of all 60 the wings so that rays of light from said lamp may shine upon all of the surfaces, and in order to intensify the said light rays and prevent them from shining directly into an observer's eyes, a combined shield and 65 reflector 13 may partially surround the lamp, and be supported by the frame 11.

In Figs. 3 and 4, the same general idea is utilized, the display surfaces 14 are suspended between the outer ends of the wings, 70 and therefore said display surfaces are at more than ninety degrees to each other, and are only three in number, and while it is not necessary that said surfaces be concave, as shown in Fig. 3, it is preferable that they 75 be constructed in this manner.

The other parts of the signs being identical, no further reference will be made thereto.

In practice, a sign constructed in accordance with either of the forms herein illustrated, may have advertisements or information displayed on the surfaces thereof, and when placed at convenient locations, will be visible from all directions, and if the 85 advertisements or information displayed is the same on all surfaces, such advertisements or information may be read by anyone passing or approaching the sign from any angle.

Of course I do not wish to be limited to 90 the exact details of construction, as herein shown, as these may be varied within the limits of the appended claims without departing from the spirit of my invention.

Having thus fully described my invention, 95 what I claim as new and useful is:

A sign including a support, three wings permanently mounted on said support spaced equi distant apart and radiating therefrom in the same horizontal plane and 100

providing a plurality of stationary display surfaces, an arched frame carrying a source of light and secured to said wings at points spaced from the intersections of said wings so as to leave the space below the source of light unobstructed, and a combined reflector and shield also supported by said frame to direct the light rays on to the wing surfaces and partially conceal the source of light from an onlooker's vision.

10 In testimony whereof, I have hereunto affixed my signature.

JAMES P. SALMON.
